UNITED STATES PATENT OFFICE.

DAVID S. HULFISH, WILLIAM J. HERDMAN, AND EGBERT S. LORIMER, OF TORONTO, ONTARIO, CANADA, ASSIGNEES, BY MESNE ASSIGNMENTS, TO GENERAL ENGINEERING AND CONSTRUCTION COMPANY, LIMITED, OF TORONTO, CANADA, A CORPORATION OF ONTARIO.

PRINTING-TELEGRAPH SYSTEM AND ALPHABET.

1,077,278.

Specification of Letters Patent. Patented Nov. 4, 1913.

Application filed March 2, 1911. Serial No. 611,780.

To all whom it may concern:

Be it known that we, DAVID S. HULFISH, a citizen of the United States of America, WILLIAM J. HERDMAN, a citizen of the United States of America, and EGBERT S. LORIMER, a citizen of the Dominion of Canada, all residents of Toronto, county of York, and Dominion of Canada, have invented a new and useful Improvement in Printing-Telegraph Systems and Alphabets, of which the following is a specification.

Our invention relates to automatic printing telegraph systems and pertains especially to that class of systems which employ a plurality of component printing elements or types, the complete legible characters being formed by impressions in proper relation and sequence from a plurality of the component types representing the various component parts of the characters to be recorded.

Our invention comprises a system of apparatus and circuits employing a control system of the simplest order whereby characters of maximum legibility may be recorded in the Roman alphabet. We accomplish this and other desirable results which will subsequently be disclosed herein by employing a form of printing pen whereby through the use of but four operating electromagnets, impressions from six printing elements or types may be selectively and successively recorded on a record sheet to form legible characters. Thus by the use of a small number of operating electromagnets we simplify the mechanism of the apparatus and by the use of a relatively larger number of printing types we permit the recording of characters in the Roman alphabet of maximum legibility.

In the figures which accompany and form a part of this specification and in which like numerals designate corresponding parts throughout; Figure 1 illustrates in diagram the circuits and apparatus at both a transmitting and receiving station and the line conductors connecting them. Fig. 2 is an enlarged diagrammatic plan view of the type blocks of our improved device showing the relation of the printing types to each other and to the blocks. Fig. 3 is a plan view in diagram of the receiver of our improved device. Fig. 4 is a sectional eleva-

tion of the receiver shown in Fig. 3 taken along the line A—A of Fig. 3. Fig. 5 shows a transmitting tape perforated to transmit with our improved device all of the characters of the Roman alphabet.

Referring to Figs. 1, 3 and 4, we will first describe the receiving apparatus and circuits that the requirements of the system may be more clearly understood. The receiver is shown in diagram at the left of Fig. 1 and comprises four electromagnets 11, 12, 15 and 16 connected in multiple in pairs to the line conductors and ground. The line conductors 24 and 25 are connected to the conductors connecting electromagnets 11 and 16 and 12 and 15 respectively. The windings of the electromagnets are so placed on their cores that a positive impulse of current over line conductor 24 flows in a counter-clockwise direction through the helix of electromagnet 16 to ground and in a clockwise direction through the helix of electromagnet 11 to ground, thus inducing a south pole on the lower extremity of magnet 16 and a north pole on the lower extremity of magnet 11. A negative impulse of current through the same line conductor and magnets to ground reverses the polarity of the lower extremities of magnets 16 and 11. Similarly a positive impulse of current over line conductor 25 through electromagnets 15 and 12 to ground induces a south pole and a north pole upon the lower extremities of magnets 15 and 12 respectively, while a negative impulse of current through the same line conductor and magnets to ground, reverses the polarity of the lower extremities of these magnets. A polarizing solenoid 23 encircles electromagnets 11, 12, 15 and 16 and is supplied with energizing current from a local battery 22 or other suitable source of current and induces when energized, like poles on the extremities of the electromagnets, north on the lower ends, Fig. 4.

A plurality of non-magnetic operating levers 1, 2, 5 and 6 provided with armatures as 41 and 45 Fig. 4 are pivoted for limited rotation in diagonal slots 11', 12', 15' and 16' in a rectangular, non-magnetic base 30 to which the field solenoid 23 and electromagnets 11, 12, 15 and 16 are rigidly attached. Curved leaf springs 7, 14, 8 and 13

are attached to the base 30 and bear upon the upper edges of the operating levers 1, 2, 5 and 6 respectively.

The type blocks 9 and 10 each carry rigidly attached to their under surface three printing elements or types arranged as shown in Fig. 2. Printing elements 1', 2² and 4⁴ are each divided into four arbitrary units of length while printing element 3³ is, when measured lineally along the type block 10, four of these arbitrary units in length. Type element 2² is spaced on type block 9 as shown a distance of two units of its length removed from type element 4⁴, while type element 6⁶ is spaced on type block 9 a distance of five units away from type element 4⁴. Type element 1' is spaced on type block 10 a distance of one unit of its length away from type element 3³, while type element 5⁵ is spaced a distance of six units from type element 3³.

Type blocks 9 and 10 are carried on the operating levers 1, 2, 5 and 6 in such relation to each other that type element 3³ is separated lineally from type element 4⁴ by one unit of type element length.

A prism-shaped anvil 27 is placed opposite the type blocks 9 and 10 and presents three printing faces to the printing elements. A screw 28 serves to adjust the anvil in its distance from the printing types.

A tape 27' sensitized with any chemical compound for electrolytic printing, rests on the surface of the anvil and is carried longitudinally over the printing faces of the anvil by means of the set of rollers as shown.

A form of transmitter is shown at the right of Fig. 1 and comprises a pair of direct current dynamos 17 and 18 or other source of current, their terminals of opposite polarity being connected together and to ground 26, while the positive terminal of dynamo 18 is connected to brushes 19² and 19⁴ and the negative terminal of dynamo 17 is connected to brushes 19' and 19³. A flexible brush 20 is of sufficient width to bear upon both brushes 19' and 19² and make contact therewith. A brush 21 is of sufficient width to bear upon both brushes 19² and 19⁴ and make contact therewith. Brushes 20 and 21 are connected to line conductors 24 and 25 respectively and are normally held out of contact with their adjacent pairs of brushes by transmitting tape 29.

It will be noted that by a proper transverse spacing of the perforations in the transmitting tape 29 with respect to brushes 19' and 19², a positive or negative impulse may be sent over line conductor 24 through electromagnets 11 and 16 to ground, thereby as hitherto noted reversing the polarity of one of the magnets of that pair from its normal polarity induced by the field solenoid 23 and cause the release of its respective operating lever which under spring ten-

sion rotates type block 9 or 10 as the case may be, dependent upon the polarity of the operating impulse, to bring either printing type 1' or 6⁶ into contact with the recording tape 27'. By a proper transverse spacing of the perforations in tape 29 with respect to the brushes 19³ and 19⁴, a positive or negative impulse may be sent over line conductor 25, through electromagnets 12 and 15 to ground to cause the release of either operating lever 2 or 5 to rotate type block 9 or 10 to bring type element 2² or 5⁵ into contact with the recording tape 27'. A positive impulse over line conductor 25 and a simultaneous negative impulse over line conductor 24 will operate levers 1 and 5 to carry type block 10 downward with a movement of translation to bring type element 3³ into contact with the recording tape 27', while a positive impulse over line conductor 24 and a simultaneous negative impulse over line conductor 25 will operate levers 2 and 6 to move type block 9 downward to bring type element 4⁴ into contact with recording tape 27'. Thus it will be observed that by a predetermined transverse spacing and grouping of the perforations in transmitting tape 29, either type block 9 or 10 may be rotated to imprint its type element borne near its extremities or either type block may be moved downward substantially without rotation to imprint the type element borne near its middle portion.

Referring to Fig. 2 which may be considered to be an enlarged view of the impressions of the type elements as they would appear were all of the types imprinted on a motionless receiving surface, types 1', 2², 3³ and 4⁴ are each in length equal to the width of a complete normal character such as H. The width of a complete normal character is divided into four arbitrary units, while the types are separated from each other longitudinally by one of these units as has been hitherto explained.

Fig. 5 shows a sectional transmitting tape 29 perforated to send all of the characters necessary to transmit intelligence in the Roman alphabet. The longitudinal lines -1, +6, -2, and +5 correspond to the lines of contact of the brushes 19', 19², 19³ and 19⁴ with the brushes 20 and 21. The transverse lines are spaced a distance apart equal to or proportional to the unit of length of the printing elements 1', 2², 3³ and 4⁴, dependent upon the ratio of the speed of the transmitting and receiving tapes. Thus a perforation along the line -1 in the transmitting tape 29, will cause the imprinting of type element 1', while a perforation along the line +6 will imprint type element 6⁶. A perforation along the line -2 will imprint type element 2² and a perforation along the line +5 will imprint type element 5⁵. Perforations along the lines -1 and +5

and opposite each other will imprint type element 3³ while perforations along the lines —2 and +6 and opposite each other, will imprint type element 4⁴.

5 Conceive now the tape 29 to move from right to left as viewed in Fig. 5 between the brushes 20 and 21, and 19¹, 19², 19³ and 19⁴ of Fig. 1 at a speed which allows one transverse spacing of tape 29 to pass through the brushes while a corresponding interval in recording tape 27' is passing from right to left under the types as viewed in Fig. 2. The letter A may now be recorded as follows:—The tape 29 passes through the brushes of the transmitter until the first set of perforations along the lines +5 and +6 simultaneously permit contact between brushes 20 and 19² and 21 and 19⁴, thus sending simultaneous positive impulses of current over line conductors 24 and 25 through magnets 15 and 16 counter-clockwise to release operating levers 5 and 6 to rotate type blocks 10 and 9 respectively to simultaneously imprint types 5⁵ and 6⁶ upon the recording tape 27', and after tape 29 has moved through the transmitting brushes a distance of four tape intervals, a similarly placed pair of perforations allow contact to be made through the same brushes as before with line conductors 24 and 25, again sending simultaneous positive impulses counter-clockwise through magnets 16 and 15, again imprinting type elements 5⁵ and 6⁶ on the recording tape 27' a distance away from the previous imprints of four units, or the width of a normal character. After tape 29 has passed through the transmitting brushes a distance of five tape intervals, a pair of perforations placed along the lines —2 and +6 and opposite each other, allow a negative impulse of current and a positive impulse of current to be simultaneously sent over conductors 25 and 24 respectively, through magnets 12 and 16, thus causing operating levers 2 and 6 to move type block 9 vertically downward to imprint type element 4⁴ on the recording tape 27'. This imprint abuts at its extremities the two previous sets of imprints as these two imprints have been carried by the receiving tape a distance of five units of tape length, previous to the imprinting of type element 4⁴. After the transmitting tape 29 has passed through the brushes of the transmitter a distance of six tape intervals, a perforation along the line —1 allows a negative impulse of current to be sent over line conductor 24 through magnet 11 in a counter-clockwise direction to imprint pen face 1' which as the previous imprints on the receiving tape 27' have been carried from right to left a distance of six units of width since the last imprint allows the extremities of the imprint of type element 1' to abut 65 at its extremities, the previous imprints of

type element 5⁵ thus forming the letter A as shown in Fig. 5. The characters are separated from each other on the recording tape by a distance of four tape units or the length of a complete normal character. 70 Thus in imprinting the character B after imprinting the character A, the left hand vertical of letter B is imprinted by perforations along the lines +5 and +6 opposite each other and a distance of four tape intervals from the perforations which cause the imprinting of the right hand vertical of letter A. This causes an overlapping of the sets of perforations in the transmitting tape for a series of characters. The spacing 80 between any two characters is provided in the transmitting tape preceding the letter or character to be imprinted as in the case of the letter D which is a double spaced letter or twice the width of a normal character. The perforations to imprint the left hand vertical are spaced a distance of eight tape intervals away from the perforations which cause the imprinting of the right hand vertical of the previous character, as the 90 character D to distinguish it from the character O is provided with an imprint from type element 2² which causes it to become a double spaced character with the normal spacing between it and the previously imprinted character of the chosen four units of length of a normal character. Similarly 95 all of the characters necessary to transmit intelligence in the Roman alphabet may be recorded. 100

While we have illustrated and described one embodiment of our invention, it is to be clearly understood that we may make many changes therein without departing from the spirit or narrowing the scope of our invention. 105

Having thus described our invention, what we claim as new and desire to secure by United States Letters Patent is as follows:—

1. In a system of printing telegraphy, a plurality of operating electromagnets, a plurality of levers individually operated thereby, a plurality of type blocks each reciprocally borne by a pair of said levers, a plurality of printing types borne by each of said type blocks, and means for selectively imprinting any of said printing types. 110

2. In a system of printing telegraphy, a plurality of electromagnets, a plurality of operating levers individually operated thereby, a plurality of type blocks each reciprocally borne by a pair of said operating levers, a plurality of printing types borne by each of said type blocks, a record sheet opposite all of said printing types, means for selectively energizing said electromagnets to operate said operating levers to bring said printing types selectively into contact with said record sheet. 120

3. In a system of printing telegraphy, a 130

plurality of type blocks, a plurality of operating levers in pairs and each such pair bearing one of said type blocks, electromagnetic means for selectively imparting 5 through said operating levers either rotatory or transitory motion to said type blocks, a plurality of printing types borne by each of said type blocks and means for selectively operating said operating levers to produce 10 impressions in a predetermined sequence from said printing types.

4. In a system of printing telegraphy, a pair of type blocks, a plurality of printing types borne by each of said type blocks, a 15 pair of operating levers reciprocally attached to each of said type blocks, operating electromagnets for said operating levers, a record sheet adjacent to said printing types, means for selectively operating said operating levers to impart rotatory or transitory motion to said type blocks to bring said printing types selectively into contact with said record sheet.

5. In a printing telegraph system, a pair 25 of type blocks, a plurality of printing types borne by each of said blocks, a record sheet therefor, a pair of operating levers attached to each of said type blocks, an operating electromagnet for each of said operating 30 levers, a polarizing helix common to all of said operating magnets and adapted through said operating magnets to retain said operating levers in a normal non-operative position, means for selectively energizing said 35 operating magnets to cause said operating levers to impart either rotatory or transitory motion to said type blocks to imprint on said record sheet any of said printing types.

6. In a printing telegraph system, a plurality 40 of operating levers, a pair of type blocks each of said type blocks pivoted to the extremities of a pair of said operating levers, a plurality of type faces borne by each of said blocks, a record sheet opposite 45 all of said type faces, electromagnets for controlling the operation of said operating levers and means for selectively energizing said electromagnets to operate said operating levers to selectively depress into contact with 50 said record sheet any of said type faces.

7. In a printing telegraph system, a plurality 55 of operating levers, a pair of type blocks each pivoted to the extremities of a pair of said operating levers, a plurality of type faces borne by each of said type blocks, a record sheet opposite all of said type faces, electromagnets for controlling the operation of said operating levers, means for selec-

tively energizing said electromagnets to operate said operating levers to bring said 60 type faces singly and selectively into contact with said record sheet.

8. In a system of printing telegraphy, four electromagnets, four levers individually operated thereby, two separably movable type blocks each reciprocally borne by a pair of said levers, three types borne by each of said type blocks, and means for selectively imprinting any of said printing types. 70

9. In a printing telegraph receiver, a printing anvil, a type block having three types, two movable members adapted to move said block, and means for moving said members independently or simultaneously; 75 said type block being suspended pivotally directly upon the ends of said members and said type block and said members being so related that the operation of the first of said members will move said block to present the first of its types toward said anvil, the operation of the second of said members will move said block to present the second of its types toward said anvil, and the operation simultaneously of both of said members will 80 move said block to present the third of its types toward said anvil.

10. In a printing telegraph receiver, a printing anvil, three related printing types and two type-actuating devices, said types 90 pivotally suspended directly upon movable extremities of said devices and said types and said actuating devices being so related that the operation of one of said devices will print the first type, the operation of the 95 other of said devices will print a second of said types, and the simultaneous operation of both of said devices will print the third of said types.

11. In a system of printing telegraphy, a 100 plurality of type blocks, a plurality of operating levers in pairs, each such pair reciprocally attached to one of said type blocks, and means for selectively imparting through said operating levers either rotatory or 105 transitory motion to said type blocks.
